United States Patent Office.

JOHN ELLIS, OF WHITE PLAINS, NEW YORK.

Letters Patent No. 74,061, dated February 4, 1868.

IMPROVEMENT IN BOILERS FOR HEATING WATER.

The Schedule referred to in these Letters Patent and making part of the same.

TO ALL WHOM IT MAY CONCERN:

Be it known that I, JOHN ELLIS, of White Plains, in the county of Westchester, and State of New York, have invented a new and improved Boiler for Heating Water; and I do hereby declare that the following is a full, clear, and exact description thereof, which will enable others skilled in the art to make and use the same, reference being had to the accompanying drawings, forming a part of this specification, in which—

Figure 1 represents a front elevation of my improved boiler.

Figure 2 is a longitudinal vertical section of the same, the plane of section being indicated by the line $z z$, fig. 1.

Figure 3 is a transverse sectional elevation of the same, the plane of section being indicated by the line $y y$, fig. 2.

Figure 4 is a transverse sectional elevation of the same, the plane of section being indicated by the line $z z$, fig. 2.

Similar letters of reference indicate corresponding parts.

This invention relates to a new boiler for heating water for buildings, green-houses, and other similar purposes, and consists in arranging a series of horizontal pipes between two hollow heads, in such a manner that the water will flow at least twice through the tubes, so as to be very completely heated. The boiler is not covered with or surrounded by the ordinary expensive iron plates, but the pipes are simply arranged in brick-work, and some of the pipes form the grate of the boiler. The whole device is thus very simple and comparatively cheap—the whole boiler actually consisting only of the two heads and of the pipes connecting the same.

A represents the front head of the boiler. The same is made of double sheet-metal walls, so as to be hollow, as shown in fig. 2, and is provided with a hole, a , through it for the insertion of the fuel. The head A may also be cast into the required form. This hole can be closed by a fire-door, b , as shown. B is the rear head of the boiler, made also of double sheet-metal plates, so as to be hollow, and has also a hole, c , through it for the escape of the smoke. The head B can also be cast into the required shape. If desired, the rear head can be made without the hole c , the smoke escaping between the pipes, connecting the heads, to a suitable chimney. C C are a series of pipes, made of wrought or cast iron, or other suitable material. Their ends are fitted into the heads A and B, respectively. The whole furnace is built under a brick arch, and is surrounded by brick walls, as is clearly indicated in figs. 1 and 2. The interior of the front head A is, by means of one or more plates; (or cores,) d , divided into two or more compartments.

The water enters the lower part of the front head through a pipe or pipes, D, and, rising in the head, flows back to the rear head through those pipes, C, which communicate with the lower compartment of the head A. If only one partition, d , is in the head A, the head B will be without a partition, so that the water may rise in the head B, and may flow in the upper pipe C to the upper compartment of the head A, whence it is conducted off through pipes E. If the head A is divided by plates d into three or more compartments, the interior of the head B will also be subdivided by similar partitions, so that a still more frequent circulation of the water from one head to the other will be effected. The fire is kindled upon the lower pipes C, which are close enough together to enable the draught to circulate through the fire. The lower pipes are arranged nearly on a semi-circular line, as shown in figs. 3 and 4, so that the fuel will always fall to the centre, and in falling will be cleared of ashes. Any kind of fuel may be used in this boiler. Peat, wood, coal, or coke can be employed.

Having thus described my invention, what I claim as new, and desire to secure by Letters Patent, is—

The boiler for heating water, consisting of the two hollow heads connected by the tubes, and having no metallic sides or walls, the grate-bars being also tubular, said heads subdivided into compartments, so that the water shall circulate freely through the boiler, as herein described, for the purpose specified.

JOHN ELLIS.
